UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

BEAM HOIST AND LOCK.

Application filed May 9, 1927. Serial No. 189,762.

This invention relates to improvements in beam hoists and locks for looms and the principal object of the invention is to provide means for holding the warp beam shaft in running position which shaft is movable to a distance beyond the end of the loom to receive the beam shaft.

The present invention relates particularly to a mechanism for hoisting a warp beam of a loom to running position and for locking the warp beam in such position. It is, however, obvious that the invention may be employed for the purpose of hoisting other beams of textile machinery into, and removing the same from, normal position.

The warp beams for looms, when loaded, are very heavy and when such beams are to be mounted upon the loom, great effort is required to lift the beams into place as the parts of the loom frame and mechanism at the rear of the loom prevent the shaft of the warp beam from being brought into close proximity to the bearing. The beam must therefore be raised bodily and carried sideways a considerable distance to enable the shaft thereof to be placed upon the usual bearings at the loom side.

One of the objects of the present invention is to provide means for supporting the bearing of the beam shaft in such a manner that it may be swung from normal running position to a distance beyond the rear of the loom so that the beam shaft may be placed in the bearing and the bearing thereupon swung to its normal running position.

A further object of the invention is to provide a device of this character in which the bearing for the beam shaft, when swung to its normal position, will be normally retained in such position by the weight of the beam and bearing.

A further object of the invention relates to means for positively locking the bearing in running position to prevent possible displacement due to vibration of the loom.

A further object of the invention is to provide a sufficient leverage to enable the operator or operators readily to swing the loaded beam into running position.

Other objects and features of the invention will more fully appear from the following description and accompanying drawings and will be particularly pointed out in the claims.

Inasmuch as the present invention relates solely to the beam hoisting and locking mech-

anism, only so much of the loom is illustrated in the accompanying drawings as is necessary to show the association of the present invention therewith.

A preferred embodiment of the invention is illustrated in the accompanying drawings in which:

Fig. 1 is an elevation of a portion of the outer face of a loom and side with the beam hoisting and locking mechanism applied thereto.

Fig. 2 is a similar view showing the inner face of the loom side illustrated in Fig. 1 and also illustrating the beam hoisting and locking mechanism.

Fig. 3 is a detail rear view of the mechanism illustrated in Figs. 1 and 2.

The invention is illustrated herein as applied to a usual form of loom comprising the loom sides 1 (one of which is shown), which are connected by a transverse channel girder 2. Similar beam hoisting and locking mechanisms are, of course, provided for both sides of the loom and the description of one will apply to both.

The upper portion of the rear end of the loom side is cut away to present a shoulder 3 which serves to support the lower bearing 4 for the shaft 5 of the warp beam 6.

The usual bracket 7 carrying the whip roll 8 is mounted upon the upper end of the loom side 1. This bracket projects rearwardly beyond the end of the loom and, together with the transverse girder 2 and other mechanisms of the loom, prevent the shaft of the loaded warp beam from being brought into close proximity to the usual bearing for such shaft which is located in the recessed or shouldered portion 3 of the loom side.

The present invention comprises a movable bearing for the beam shaft which is movable to a sufficient distance rearwardly of the end of the loom to enable the beam shaft to be placed in the bearing and preferably to be locked therein and which bearing is then movable with the beam shaft mounted therein into normal running position.

In the preferred embodiment of the invention illustrated herein, each lower bearing 4 for the beam shaft 5 is in the form of a rectangular block which preferably is integral with an inwardly extending offset portion 9 of an arm 10 which extends parallel to the loom side and which arm is pivotally mounted near its lower end upon a stud 11 project-

ing inwardly from a bracket 12 which is secured to the inner face of the loom side by suitable bolts 13. The lower end of the arm 12 is provided with a rearward extension presenting a shoulder 14 which is adapted to rest against the girder 2 when the arm 10 which supports the bearing 3 is swung rearwardly to a position to receive the shaft of the beam, as illustrated in dotted lines in Fig. 1. The 5 arm 10 desirably has a boss 15 which extends the bearing of the arm upon the stud 11 and also desirably has a central, longitudinally extending strengthening rib or web 16 which merges into a cylindrical boss 17 at the upper 10 end of the arm 10. The boss 17 desirably extends at an angle to the longitudinal axis of the arm 10 and is bored to receive a cylindrical bar or lever 18 of such desirable length as will give the proper leverage to enable the 15 arm and bearing with the loaded beam supported thereon to be lifted from loading position to normal running position with comparatively little effort. The axis of the stud 11 upon which the arm 10 is mounted desirably is located approximately in the plane of the rear end of the loom side so that when the lower bearing 4 rests upon the shoulder 3, it will lie in front of the vertical plane of the rear end of the loom side. The arm 10 20 thereby effectively locks the bearing in position against rearward displacement for the bearing can only be moved rearwardly by moving it vertically and rearwardly about the pivot 11 and such vertical and rearward 25 movement of the bearing with the heavy warp beam therein requires a very considerable force.

Means desirably are provided, however, for positively locking the lower bearing in running position to avoid any possible displacement which may be caused by the vibration of the loom.

In the preferred construction illustrated herein, the bracket 12 has a laterally, preferably rectangular, extension 19 which engages the rear edge of the loom side. This extension is bored centrally to receive a clamping bolt 20 and is recessed to receive the head 21 of the bolt. A keeper 22 which is mounted 45 upon the bolt 20 and is provided with a curved end portion 23 engaging the rear face of the bearing 4 serves to clamp the bearing firmly against the shoulder 3 when the nut 24 upon the bolt 20 is set up.

The keeper desirably is provided with a longitudinally extending slot 25 through which the bolt 20 extends to permit the end 23 of the keeper to drop below the shoulder 3 on the loom side when it is desired to swing the bearing 3 from running position into loading position.

The bearing for the beam shaft is made in pivotally connected separable sections. As illustrated herein, the lower bearing 4 is a massive block of substantially rectangular

form, but having the forward upper portion thereof cut away to form an inclined face 26 in which the semi-cylindrical half of the bearing 27 for the beam shaft is formed. The upper rear end of the lower bearing member has an upwardly extending boss 28 and the upper bearing member 29 is provided with a bifurcated rear end presenting lugs 30 and 31 which are pivotally connected to the boss 28 by a pin 32. The forward portion of the upper bearing member 29 is provided with an inclined surface 33 and with a semi-cylindrical bearing surface 34, which are respectively complementary to the inclined surface 26 and semi-cylindrical surface 27 of the lower bearing member. The forward end of the upper bearing member is bifurcated to receive a clamping bolt 35 having at its lower end an eye which is pivotally mounted upon a pin 36 in the lower bearing member. The bolt 35 has a nut 37 and a washer 38 adapted, when set up, to clamp the upper and lower bearing members firmly together.

The warp beam is illustrated in running position in full lines in Fig. 1. When it is desired to remove and replace the warp beam, the nut 24 is backed off, thus permitting the keeper to drop below the plane of the shoulder 3, thus releasing the bearing 4. The operator may then grasp the handle lever 18 and by pressing down upon it, easily swing the bearing and its supporting arm about the pivot 11 into the loading position illustrated in dotted lines in Fig. 1. The nut 37 upon the bolt 35 may then be released and the bolt 35 swung about its pivot 36, thereby freeing the upper bearing which may then be swung into the depending position illustrated in dotted lines in Fig. 1. The warp beam may then be easily removed. A loaded warp beam may then be brought by a truck into such position that the shaft of the warp beam is in proximity to the bearing 27 of the lower bearing block and can be readily inserted in the bearing. The upper bearing member 29 may thereupon be swung into position and locked therein by swinging the bolt 35 into the bifurcated end thereof and screwing down the nut 37. The operator can then readily swing the bearing with the beam mounted therein into running position by lifting the lever 18 which affords him sufficient leverage to enable him to move the beam to running position with comparative ease. The keeper 22 will then be raised until the end 23 engages the rear face of the bearing 4, as illustrated in Fig. 1, and the bearing clamped in position by setting up the nut 24 upon the bolt 20.

Similar movable right and left-hand bearings are, of course, provided for the respective ends of the warp beam shaft.

By reason of this construction, a great saving is accomplished in the time required for removal and replacement of warp beams, as well as a great reduction of the strength re-

quired to remove and replace the warp beams.

It is obvious that the invention herein may be employed on other types of looms to which it is applicable and that the bearings and arms and the brackets thereof may be constructed in any such manner as may be necessary to enable the invention to be applied to a particular type of loom.

It will be understood that the embodiment 10 of the invention particularly disclosed herein is of an illustrative character and that various modifications in form, construction and arrangement of the parts may be made within the spirit and scope of the claims.

15 Having thus described the invention, what is claimed as new, and desired to be secured by Letters Patent, is:

1. A beam hoist and lock for looms comprising an arm pivotally mounted upon and within each loom side having a bearing member for the beam shaft normally resting upon and supported by the shoulder of the loom side and movable about said pivot to a position rearwardly of the loom side to receive 25 the beam shaft and releasable locking means mounted on said loom side engaging said bearing member above said shoulder and acting to clamp said bearing member upon said shoulder.

2. A beam hoist and lock for looms comprising an arm pivotally mounted upon and within each loom side having a bearing member for the beam shaft normally resting upon and supported by the shoulder of the loom 35 side and movable to a position rearwardly of the loom side to receive the beam shaft, and a lever extending upwardly and outwardly from the upper portion of said arm and detachably secured thereto, operable to swing 40 said bearing member from and to operating position.

3. A beam hoist and lock for looms comprising an arm pivotally mounted upon and within each loom side having an outwardly offset bearing member for the beam shaft normally resting upon and supported by the shoulder of the loom side and movable to a position rearwardly of the loom side to receive the beam shaft, and locking means 50 mounted on the loom side movable into and

out of engagement with the rear face of said bearing member for clamping the bearing member upon the shoulder of the loom side.

4. A beam hoist and lock for looms having 55 loom sides and a rear cross girder connecting the same comprising an arm pivotally mounted upon each loom side having an outwardly offset bearing member for the beam shaft normally resting upon and supported by the shoulder of the loom side and movable to a 60 position rearwardly of the loom side to receive the beam shaft, and a shoulder on said arm adapted to engage said rear cross girder to limit the rearward movement of said arm.

5. A beam hoist and lock comprising a 65 bracket secured to the inner face of each loom side and having an extension overlapping the end of the loom side, an arm pivotally mounted upon the bracket having an outwardly offset lower bearing member normally resting 70 upon a shoulder of the loom side, a complementary upper bearing member pivotally connected to said lower bearing member, means for clamping said bearing members together, a keeper movably mounted upon said 75 bracket extension having means to engage said lower bearing, and a clamping screw engaging said bracket and said keeper.

6. A beam hoist and lock comprising a 80 bracket secured to the inner face of each loom side and having an extension overlapping the end of the loom side, an arm pivotally mounted upon the bracket having an outwardly offset lower bearing member normally resting upon the shoulder of the loom 85 side, a complementary upper bearing member pivotally connected to said lower bearing member, means for clamping said bearing members together, a keeper having means to engage said lower bearing member and provided with a slot, a bolt passing through said 90 slot to permit bodily vertical movement of said keeper having a head mounted in said bracket extension and a nut on said bolt operable to clamp said keeper upon said bearing.

In testimony whereof, I have signed my name to this specification.

HARRY A. DAVIS.
